UNITED STATES PATENT OFFICE.

J. D. BURDICK, OF ASHWAY, RHODE ISLAND.

IMPROVED BLIND-SLAT FASTENING.

Specification forming part of Letters Patent No. 44,072, dated September 6, 1864.

To all whom it may concern:

Be it known that I, J. D. BURDICK, of Ashway, in the county of Washington and State of Rhode Island, have invented a new and Improved Fastening for Blind-Slats; and I do hereby declare that the following is a full, clear, and exact description of the same, reference being had to the accompanying drawings, making a part of this specification, in which—

Figure 1 is an inner side view of a window-blind with my invention applied to it. Fig. 2 is a vertical section of the same taken in the line $\alpha\alpha$, Fig. 1.

Similar letters of reference indicate corresponding parts in the two figures.

This invention relates to a new and improved fastening for securing the slats of window-blinds in an open or closed state or at any point between those two positions. The object of the invention is to obtain a simple fastening for the purpose specified, one which may be constructed at a reasonable cost, not be liable to get out of repair, and one which will not interfere at any time or in any position in which it may be adjusted with the window-sash.

To this end the invention consists in the employment or use of a bent lever, a spring, and connecting-rod arranged and applied in such a manner that the lever in operating the slats is turned or adjusted in a plane parallel with the window-blind, as hereinafter described.

To enable those skilled in the art to fully understand and construct my invention, I will proceed to describe it.

A represents a window-blind, which may be constructed in the ordinary way, the slats being designated by a , and the rod to which the slats are attached being designated by b .

B is a case or socket, which is attached by screws c to the lower cross-bar, d , of the blind. This case or socket is constructed of metal, open at its upper end and having a slot, e , in its bottom to admit of the working of a bent lever, C , which is fitted loosely on a rod or axis, D , in the case or socket B , the rod or axis D being at right angles with the cross-bar d , and the lever C , when turned or operated, moving in a plane parallel with the blind A . The longer arm, f , of the bent lever C is provided with a knob, g , and the

end of the shorter arm, h , is perforated to receive a hook, i , at the lower end of a rod, E , the upper end of which is attached to one side of the slat-rod b by a screw, j . On the rod or axis D of the bent lever C there is placed an india-rubber spring, E' , one end of which bears against the inner side of the case or socket B and the other against the lever C , as shown clearly in Fig. 2. The upper edge of the outer side of the case or socket B is provided with a notch or recess, k , to receive the long arm f of the lever C when said arm is in a vertical position.

From the above description it will be seen that by turning the lever C the rod E will actuate or turn the blind-slats a , and when the bent lever C is turned to the left to the extent of its movement, as shown in tint in both figures, the blind-slats will be secured in a closed state, and when turned to the right to the full extent of said movement, as shown in red outline, the slats will be secured in an open state. (See Fig. 2, in which the slats are shown in an open state in red outline.) When the lever C is turned so that the long arm f of the lever will fit in the notch or recess k , the slats will be secured in a half-open state. The spring E' keeps the arm f in the notch or recess k , and when it is desired to turn the arm f of the lever C out from the notch or recess, the lever C is first pressed a little inward, so as to compress the spring E' and admit of the arm f being freed from the notch or recess. The bent lever C will turn casually when the slats a are in an open and a closed state, for the reason that the short arm h of the lever, when the slats a are in such positions, is in line, or nearly so, with the rod or axis D , thereby forming a lock.

The rod E has a semicircular bend, t , made in it near its lower end, so that the rod will clear the spring E' when the lever C is turned to the right and the slats a are in an open state.

I would remark that if necessary the upper edge of the outer side of the case or socket B may have a notch or recess similar to k made in it between k and the ends of the case or socket, so that the slats may be secured in an intermediate position between a half-open and an open and a closed state.

In consequence of operating the rod E through the medium of the lever C , arranged as shown, no parts of the fastening can at

any time come in contact with the window-sash, as they do not project far enough out from the blind.

Instead of the india-rubber spring E', a spiral spring may be used.

Having thus described my invention, what I claim as new, and desire to secure by Letters Patent, is—

The bent lever C, fitted within a suitable case or socket, B, and applied to the blind A, so as to turn or work in a plane parallel there-

with, in combination with the rod E, attached to the short arm h of the lever C, and to the slat-rod b, and the spring E', fitted on the rod or axis D of the lever, between said lever and the inner side of the case or socket B, substantially as and for the purpose herein set forth.

J. D. BURDICK.
